MACHINE FOR OPERATING ON SHOES

Bernhardt Jorgensen, Marblehead, Mass., assignor to United Shoe Machinery Corporation, Flemington, N. J., a corporation of New Jersey

Application January 25, 1941, Serial No. 375,891

24 Claims. (Cl. 12—4)

This invention relates to machines for operating on shoes, and is herein illustrated as applied to a pulling-over machine of the same general type as disclosed in United States Letters Patent No. 1,029,387, granted on June 11, 1912, on an application of R. F. McFeely. It is to be understood, however, that the invention is not limited to machines of that type and that in various novel aspects also it is not limited to pulling-over machines.

An object of the invention is to provide improved means for slitting the margin of an upper as an aid to lasting or to an operation prior to lasting, a more immediate object being to slit the upper materials at the opposite sides of the toe to facilitate removal of the margin of one or more inner layers of the materials around the toe when the toe end of an upper is lasted, for example, with cement. It is a further object of the invention to provide upper-slitting means which may be readily incorporated in existing machines, such as pulling-over machines of the type illustrated in the above-mentioned Letters Patent. For the purposes in view, the invention in its illustrated embodiment provides upper-slitting knives which are guided in their movements by the side grippers of a machine of the above-mentioned type to slit the margin of the upper in predetermined relation to these grippers while the upper is held under tension by the grippers, the knives being so supported and controlled that the grippers determine their positions lengthwise of the last but are movable relatively to them widthwise of the last in operating on the upper in the manner characteristic of such machines. In the construction shown the knives are supported on a knife carrier which is mounted for swinging movements heightwise of the last and are held yieldingly against guiding faces on the grippers by springs supported on the carrier. It will be evident that such upper-slitting means may be incorporated in an existing machine without in any way affecting the construction of the grippers or of their operating means.

The invention further provides simple and effective mechanism, likewise readily applicable to existing machines, for imparting operative movement to the upper-slitting means. As herein illustrated, operative movement is imparted to the above-mentioned knife carrier by a fluid-operated device to which compressed air is admitted and from which the air is released automatically in proper time relation to other operations of the machine, the knife carrier being returned by a spring when the air is thus released.

For controlling the flow of air to and from the fluid-operated device the construction herein shown comprises a valve which is moved into position to admit the air to the device and is then returned by a spring into position to release the air in response to continuous movement in one direction of a valve-controlling member. For thus controlling the valve use is conveniently made of a slide with which a machine of the illustrated type is provided for operating devices which clamp the upper at the opposite sides of the last while it is held under tension by the grippers. The knives are, therefore, quickly operated to slit the upper and are then immediately returned to their starting positions.

The above and other features of the invention, including various novel details of construction and combinations of parts, will now be more particularly described with reference to the accompanying drawings and thereafter pointed out in the claims.

In the drawings,

Fig. 1 is a view in right-hand side elevation of the upper portion of a machine of the type illustrated in the above-mentioned Letters Patent with the present invention embodied therein, the parts being shown in the positions which they occupy after the pulling of the upper but prior to the slitting of its margin;

Fig. 2 is mainly a plan view showing the upper-clamping devices and parts associated therewith;

Fig. 3 is a perspective front view of a portion of the machine, showing the parts as they appear at the end of the upper-slitting operation;

Fig. 4 is a view partly in left-hand side elevation and partly in section, showing certain parts as they appear at the same time in the operation of the machine as in Fig. 1;

Fig. 5 is a section on the line V—V of Fig. 2; and

Fig. 6 is a perspective view of the toe portion of the shoe after the operation of the machine thereon.

As common in machines of the illustrated type, the machine herein shown is provided with a toe-end gripper 2 and with a pair of opposite side grippers 4 for gripping and pulling an upper, respectively, at the end of the toe and the sides of the forepart. Each of the side grippers 4 is a duplex gripper, comprising front and rear pairs of jaws 6 and 8 for gripping the upper comparatively near the end of the toe and farther from the end of the toe, respectively. The two pairs of jaws 6 and 8 are mounted, respectively, on gripper casings 10 and 12 through which upper-pulling

movements heightwise of the last are imparted to the jaws, the position of the shoe heightwise in the upper-pulling operation being determined by engagement of the insole with a shoe rest 14. A machine of this type comes to a stop after the pulling of the upper and while the grippers are holding it under tension, as illustrated in Fig. 1, to permit the operator to make any necessary adjustment of the upper relatively to the last. After the machine has again been started, upper-clamping devices 16 (Fig. 2) are moved into positions to clamp the upper against the sides of the forepart of the last and to support the shoe against downward movement when the margin of the upper is thereafter wiped inwardly over the insole and fastened to the insole. These upper-clamping devices are carried by side clamp arms 18 which are pivotally mounted at 20 on the head of the machine and are provided with inwardly extending gear segments 22 in engagement with rack bars 24. The rack bars are operated yielding through springs 26 by a horizontally movable slide 28 provided with a roll 30 which is engaged by a cam 32 (Fig. 1) to operate the slide, as fully disclosed in the previously mentioned Letters Patent. The swinging of the upper-clamping devices 16 inwardly into engagement with the shoe is effected by rearward movement of the slide 28 (i. e., movement toward the right as the parts are viewed in Figs. 1 and 2). Return movement of the slide to return the upper-clamping devices is effected, when permitted by the cam 32, by a spring 34 connected at one end to a bracket 36 fast on the slide and at the other end to a clip 38 fast on the head of the machine. Following the clamping of the shoe by the clamping devices 16, the margin of the upper is wiped inwardly over the insole by wipers carried, respectively, by a front arm 40 and opposite side arms 42, only one of the side arms being visible in the drawings (Fig. 1). The wiper on the front arm is shown at 43. These arms are swung inwardly toward the shoe thus to operate the wipers and they act in their inward swinging movements to cause the grippers, which are also swung inwardly, to release the upper. The arms 40 and 42 also carry, as usual, devices for driving tacks at the end and the sides of the toe to fasten the upper in pulled-over position, as illustrated in Fig. 6, after the inward swinging movements of the arms. After the driving of the tacks the parts of the machine are returned to their starting positions.

For purposes of this invention there is secured to the head of the machine a bracket 44, and pivotally mounted on pins 46 on this bracket to swing about an axis extending widthwise of the last is a U-shaped knife carrier 48. Pivotally mounted on a pin 50 on each of the arms of the U-shaped carrier 48 is a knife holder 52 on which is secured an upper-slitting knife 54. These knives are pressed against the front or toewardly facing surfaces of the front side gripper casings 10 by means of springs 56 on the carrier 48 which tend to swing the holders 52 rearwardly about the pins 50. The front surfaces of these casings, therefore, and the gripper jaws below the casings serve as guides for the knives in their upper-slitting movements heightwise of the last, so that the slits formed thereby in the margin of the upper materials are in predetermined relation to the front side grippers. It will be evident that these grippers determine the positions of the knives lengthwise of the last in the upper-slitting operation, but are movable relatively to the knives

widthwise of the last, the knives being wide enough to maintain contact with the grippers in all positions of the latter widthwise of the last. A spring 58 connected to the bracket 44 and to one arm of the knife carrier 48 tends to retract the knives heightwise of the last and holds them initially in retracted positions determined by engagement of that arm of the carrier with the bracket 44, as illustrated in Fig. 4. Under usual conditions the knives in their retracted positions are in contact with the grippers, as illustrated in Fig. 4. In order, however, to prevent interference between either of the knives and the side arm 42 at the same side of the machine when this arm is swung inwardly, in case the gripper at that side of the machine should be adjusted so far toward the heel end of the last as to involve danger of such interference, each of the knife holders 52 has formed thereon a lug 59 (Fig. 4) arranged to engage a portion 60 of the head of the machine to limit rearward swinging movement of the knife under the influence of the spring 56. It will be evident that even though either knife 54 is thus positioned initially out of contact with the corresponding gripper casing 10, it will be swung into contact with the casing by the spring 56 immediately after the beginning of the operative movement of the knife carrier 48.

To operate the knives 54 the carrier 48 is swung against the resistance of the spring 58 by a plunger or piston 61 which engages one arm of the carrier and is movable in a cylinder 62 formed as part of the bracket 44. The operative movement of the knives is adjustably limited, to determine the depth of the slits in the upper, by engagement of a bumper 64 on the carrier 48 with a screw 66 threaded in the bracket 44. The plunger 61 is operated by compressed air admitted to the cylinder 62 through a pipe 68. Air is supplied to the pipe 68 from a pipe 70 (Figs. 1 and 5) which leads from any suitable source of compressed air, such as a factory supply or a suitable pump. Admission of the compressed air to the pipe 68 and the exhaust of air therefrom are controlled by a sleeve valve 72 which is slidably movable vertically on a short tube 74 clamped between a bracket 76 fast on the head of the machine and a plate 78 secured to the bracket by rods 80 and nuts 82. The lower end of the tube 74 is in communication with the pipe 70 and its upper end with the pipe 68. The tube has therein a partition 84 which closes communication between its upper and lower ends, and extending through it above and below this partition, respectively, are ports 86 and 88. The valve 72 is provided with an annular chamber 90 through which communication is established between the ports 86 and 88 when the valve is moved upwardly from its initial position in engagement with a boss 92 on the bracket 76. The valve is held normally in engagement with this boss by a spring 94 located between it and the plate 78. The valve is moved upwardly against the resistance of the spring by an arm 96 pivotally mounted on a pin 98 on the bracket 76, this arm having pivotally mounted thereon a shoe 100 (Fig. 2) which extends into an annular groove 102 in the valve. For operating the arm 96 there is provided a bar 104 pivotally mounted on a pin 106 which is carried by the previously mentioned bracket 36 fast on the slide 28. This bar has a shoulder 108 arranged to engage a block 110 fast on the arm 96 to swing the arm upwardly and thus to lift the valve 72 in response to that movement of the slide 28 whereby the shoe-clamping devices 16 are swung into engagement.

ment with the shoe. A spring 112 engaging a tail end of the bar 104 holds the bar normally down on the block 110 as illustrated in Fig. 5. Before the slide 28, however, completes its operative movement a finger 114 also fast on the arm 96 engages the bar 104 underneath and lifts it out of contact with the block 110, thus releasing the valve 72 to the action of the spring 94 which immediately returns the valve to its initial exhaust position, interrupting communication between the ports 86 and 88 and opening the ports 86 to 10 permit the air to escape from the cylinder 62. It will thus be seen that in response to the single continuous movement of the slide 28 the valve 72 is moved to inlet position to admit compressed air to the cylinder 62 to operate the upper-slitting knives 54 and is then released to cause it to return to its initial position and open the ports 86 to exhaust, whereupon the knives are returned by the spring 58.

The manner of operation of the machine, in so far as it is of interest with reference to the present invention, will now be briefly summarized. The operator presents a shoe to the machine with the margin of the upper between the open gripper jaws and with the insole against the shoe rest 14, and then starts the machine, whereupon the grippers grip the margin of the upper and pull it heightwise of the last. The machine then comes to a stop with the upper held under tension to permit the operator to make any necessary adjustment of the upper relatively to the last by manipulating the grippers. When the machine is again started, the upper-clamping devices 16 are swung inwardly to their upper-clamping positions by rearward movement of the slide 28. By this movement of the slide the valve 72 is lifted through the action of the bar 104 on the arm 96 to admit compressed air to the cylinder 62, whereupon the plunger 61 is moved downwardly to impart to the knives 54 their upper-slitting movements (Fig. 3) limited by engagement of the bumper 64 with the screw 66, the knives being guided in these movements by the front side-gripper casings 10 and their jaws 6. In response to further movement of the slide 28 the arm 96 is released by the bar 104, whereupon the spring 94 returns the valve 72 to exhaust position to release the air from the cylinder 62. The spring 58 then returns the knives 54 to their initial positions and returns the plunger 61. Thereafter the front arm 40 and the side arms 42 are swung inwardly to cause the wipers which they carry to wipe the margin of the upper over the insole, the several grippers also being swung inwardly and releasing the upper in response to the action of the arms thereon. In this operation the side arms move relatively to the knives 54. Tacks are then driven to fasten the upper in the manner illustrated in Fig. 6. Thereafter the parts of the machine not already in their starting positions are returned to such positions. It will be understood that in response to the return movement of the slide 28 the bar 104 again assumes the relation to the block 110 on the arm 96 in which it is shown in Fig. 5.

Having described the invention, what I claim as new and desire to secure by Letters Patent of the United States is:

1. In a machine for operating on shoes, the combination with grippers for gripping the margin of an upper at opposite sides of a last and for pulling the upper heightwise of the last, of knives guided by said grippers for movements

heightwise of the last to slit the margin of the upper held by the grippers, the grippers being movable widthwise of the last relatively to said knives.

- 5 2. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, and means for supporting and operating said knives, the grippers being arranged to determine the positions of the knives lengthwise only of the last.
- 15 3. In a machine for operating on shoes, the combination with grippers for gripping the margin of an upper at opposite sides of a last and for pulling the upper heightwise of the last, each of said grippers comprising a pair of upper-gripping jaws and a casing extending heightwise of the last and supporting said jaws, of knives guided by toewardly facing surfaces of the gripper casings for movements heightwise of the last to slit the margin of the upper held by the jaws, the grippers being movable widthwise of the last relatively to said knives.
- 20 4. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, means movably mounted independently of the grippers for supporting and operating said knives, and means for maintaining the knives in positions to be guided by the grippers while permitting movements of the grippers widthwise of the last relatively to the knives.
- 25 5. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, means movably mounted independently of the grippers for supporting and operating said knives, and spring means tending to move the knives toward the grippers relatively to said supporting means to maintain them yieldingly in positions to be guided by the grippers.
- 30 6. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, means supporting said knives and movable thus to operate them, the knives being so mounted as to permit them to move relatively to said supporting means in directions lengthwise of the last, and springs tending to move the knives lengthwise of the last toward the grippers to maintain them in positions to be guided by the grippers.
- 35 7. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, a knife carrier supported independently of the grippers and movable thus to operate the knives, knife holders
- 40 75

movably mounted on said knife carrier to permit the knives to move relatively to the carrier in directions lengthwise of the last, and spring means tending to move said holders each in one direction and thereby to maintain the knives in positions to be guided by the grippers.

8. In a machine for operating on shoes, the combination with grippers for gripping the margin of an upper at opposite sides of a last and for pulling the upper heightwise of the last, of knives guided by said grippers for movements heightwise of the last to slit the margin of the upper held by the grippers, a knife carrier mounted for swinging movement about an axis extending widthwise of the last thus to operate the knives, knife holders pivotally mounted on said knife carrier for swinging movements each about an axis extending widthwise of the last, and spring means tending to swing said holders each in one direction to maintain the knives in positions to be guided by the grippers.

9. In a machine for operating on shoes, the combination with grippers for gripping the margin of an upper at opposite sides of a last and for pulling the upper heightwise of the last, each of said grippers comprising a pair of upper-gripping jaws and a casing extending heightwise of the last and supporting said jaws, of knives guided by toewardly facing surfaces of the gripper casings for movements heightwise of the last to slit the margin of the upper held by the jaws, means mounted independently of the grippers for supporting and operating said knives, and spring means for yieldingly maintaining the knives in contact with those surfaces of the gripper casings.

10. In a machine for operating on shoes, the combination with grippers for gripping the margin of an upper at opposite sides of a last and for pulling the upper heightwise of the last, of knives guided by exterior faces of said grippers for movements heightwise of the last to slit the margin of the upper held by the grippers, holders for said knives, and supporting means on which said holders are pivotally mounted, said supporting means being mounted independently of the grippers for swinging movement heightwise of the last to operate the knives.

11. In a machine for operating on shoes, the combination with means for gripping the margin of an upper on a last and for pulling the upper, of upper-slitting means movable to slit the margin of the upper while it is held by said upper-gripping means, a fluid-operated device for operating said upper-slitting means, and means for admitting operating fluid to said device and for releasing the fluid therefrom.

12. In a machine for operating on shoes, the combination with means for gripping the margin of an upper on a last and for pulling the upper, of upper-slitting means movable to slit the margin of the upper while it is held by said upper-gripping means, a fluid-operated device for imparting upper-slitting movement to said upper-slitting means, and a spring for imparting return movement to the upper-slitting means.

13. In a machine for operating on shoes, the combination with means for gripping the margin of an upper on a last and for pulling the upper, of upper-slitting means movable to slit the margin of the upper while it is held by said upper-gripping means, a fluid-operated device for operating said upper-slitting means, a controlling member, and means for admitting operating fluid to said device and for releasing the fluid there-

from in response to a continuous movement of said controlling member in one direction.

14. In a machine for operating on shoes, the combination with means for gripping the margin of an upper on a last and for pulling the upper, of upper-slitting means movable to slit the margin of the upper while it is held by said upper-gripping means, a fluid-operated device for imparting upper-slitting movement to said upper-slitting means, valve mechanism for admitting compressed air to said device and for releasing the air therefrom, and a spring for imparting return movement to said upper-slitting means when the air is released from said device.

15. In a machine for operating on shoes, the combination with means for gripping the margin of an upper on a last and for pulling the upper, of upper-slitting means movable to slit the margin of the upper while it is held by said upper-gripping means, a fluid-operated device for imparting upper-slitting movement to said upper-slitting means, a valve for admitting compressed air to said device and for releasing the air therefrom, a controlling member, means for operating said valve to admit the air to said device and then to release the air therefrom in response to a continuous movement of said controlling member in one direction, and a spring for imparting return movement to the upper-slitting means when the air is released from said device.

16. In a machine for operating on shoes, the combination with means for gripping the margin of an upper on a last and for pulling the upper, of upper-slitting means movable to slit the margin of the upper while it is held by said upper-gripping means, a fluid-operated device for operating said upper-slitting means, a valve movable from exhaust to inlet position to admit compressed air to said device, a spring for returning the valve to exhaust position to release the air from said device, and means for moving said valve to inlet position and for then releasing it to cause it to be returned by its spring to exhaust position while the upper is held by the upper-gripping means.

17. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, and fluid-operated means for operating said knives.

18. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, a knife carrier supporting said knives and mounted for swinging movement heightwise of the last, and a fluid-operated device for operating said knife carrier.

19. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, a knife carrier supporting said knives and movable heightwise of the last to operate them, a fluid-operated device for imparting operative movement to said knife carrier, means for admitting compressed

air to said device and for releasing the air therefrom, and a spring for returning the knife carrier when the air is released from said device.

20. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, fluid-operated means for imparting upper-slitting movements to said knives, valve mechanism for admitting compressed air to said fluid-operated means and for releasing the air therefrom, and spring means for returning the knives when the air is thus released.

21. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, a knife carrier supporting said knives and movable heightwise of the last to operate them, a fluid-operated device for operating said knife carrier, valve mechanism for admitting compressed air to said device and for releasing the air therefrom, a controlling member, and means for operating said valve mechanism to admit the air to said device and to release the air therefrom in response to a continuous movement of said controlling member in one direction.

22. In a machine for operating on shoes, the combination with grippers for gripping the margin of an upper at opposite sides of a last and for pulling the upper heightwise of the last, of knives movable heightwise of the last adjacent to said grippers to slit the margin of the upper while the upper is held by the grippers, a knife carrier supporting said knives and movable heightwise of the last to operate them, a fluid-operated device for operating said knife carrier,

5 a valve movable from exhaust to inlet position to admit compressed air to said device, a spring for returning the valve to exhaust position to release the air from said device, a controlling member, and means for moving the valve to inlet position and for then releasing it to the action of its spring in response to a continuous movement of said controlling member in one direction.

10 23. In a machine for operating on shoes, the combination with grippers for gripping the margin of an upper at opposite sides of a last and for pulling the upper heightwise of the last, of knives movable heightwise of the last to slit the margin of the upper adjacent to said grippers while the upper is held by the grippers, fluid-operated means for operating said knives, devices for clamping the upper at the opposite sides of the last, a slide movable to apply said clamping devices to the upper, and means for admitting operating fluid to said fluid-operated means and for then releasing the fluid therefrom in response to movement of said slide in one direction.

20 24. In a machine for operating on shoes, the combination with grippers for gripping the margin of an upper at opposite sides of a last and for pulling the upper heightwise of the last, of knives movable heightwise of the last to slit the margin of the upper adjacent to said grippers while the upper is held by the grippers, fluid-operated means for operating said knives, devices for clamping the upper at the opposite sides of the last, a slide movable to apply said clamping devices to the upper, a valve movable to admit operating fluid to said fluid-operated means, a spring for moving the valve reversely to release the fluid from said means, and mechanism for moving said valve into position to admit the fluid and for then releasing it to the action of its 30 spring by the movement of said slide in one direction.

BERNHARDT JORGENSEN.
